UNITED STATES PATENT OFFICE.

CHARLES S. BAVIER AND EDWIN F. BANFIELD, OF NEW YORK, N. Y.

FABRIC PACKING.

1,040,259.

Specification of Letters Patent.

Patented Oct. 8, 1912.

Application filed November 15, 1911. Serial No. 660,499.

To all whom it may concern:

Be it known that we, CHARLES S. BAVIER and EDWIN F. BANFIELD, both citizens of the United States, and residents of the ⁵ borough of Manhattan, city, county, and State of New York, and borough of Brooklyn, in said city, county, and State of New York, respectively, have invented certain new and useful Improvements in Fabric Packing, of ¹⁰ which the following is a specification.

This invention relates to improvements in fabric packing, especially for engines and motors.

The invention consists in the combination ¹⁵ of separate independently movable filamentary bodies such as shavings of lead or its alloys, finely fractured wood such as sawdust, and fabric such as cheese cloth. For brevity we hereinafter use the term "lead" ²⁰ to signify not only metallic lead but any alloy thereof suitable for packing.

Lead and its alloys have properties rendering them advantageous for packing. But the pieces of metal must be kept separated ²⁵ and prevented from coalescing or being amalgamated together when in use; and hitherto no means has been known for preventing such coalescing or amalgamating. But we have found that lead shavings will ³⁰ remain separate and independently movable when they are combined or mixed with particles of finely fractured wood such as sawdust, and especially when layers of said shavings are separated by a strip or strips ³⁵ of fabric such as cheese cloth.

We find that the said fabric is useful in holding the filaments and the shredded wood in their proper position in the packing, preventing their gathering or bunching in certain parts only of the packing, and preserving the desired uniformity of structure in all parts of the packing when in use.

Referring to the drawings which accompany the specification, to aid the description, Figure 1, is a plan view of a strip of fabric with lead filaments. Fig. 2 is an edge view of a strip of fabric with lead filaments. Fig. 3 is a perspective view of one form of the complete packing. Fig. 4, shows two strips of fabric with lead filaments between them.

On a strip of any suitable fabric A, preferably woven cheese cloth, of proper width, are spread one or more layers of separate ⁵⁵ and independent shavings of lead B together with the particles of finely fractured

wood. Said shavings of lead are preferably in the form of flat filaments, as indicated. In order to produce the necessary thickness and body of the packing, other strips of fabric and layers of lead and fractured wood may be laid on alternately, and the same result of having alternate layers of fabric and lead and fractured wood is conveniently attained by rolling the lead covered fabric ⁶⁰ into a spiral roll, as indicated in Fig. 3. The external edge of the fabric A may then be stitched to the underlying fabric as at a, whereby the packing is retained in the roll form. Of course the packing may also be ⁶⁵ made in sheets, in ring form, or any other desired form.

The layers of fabric A between the layers of lead B effectually prevent the filaments of lead from injuriously coalescing or amalgamating under the pressures and other conditions to which the packing is subjected when in use; and the quality of the packing is improved by sprinkling the said fabric A and lead filaments B, one or all, with shredded wood, preferably in the form of sawdust. ⁷⁵ ⁸⁰

When in use, the part of fabric in contact with the moving part of engine or motor, as piston rod, very soon wears away and ⁸⁵ the lead lubricates the moving part, while, at the same time, the packing keeps the joint tight.

Packing constructed as hereinbefore described, is useful for making tight joints ⁹⁰ around piston rods of engines and motors, and for many other purposes. The independency of the lead filaments permits them to freely "work" and thereby to adapt the packing to form steam and water tight joints ⁹⁵ around piston rods and in other places.

Now having described our improvements, we claim as our invention—

1. As a new article of manufacture, packing composed of independently movable substantially flat lead strips and particles of finely fractured wood between the several lead strips, substantially as described. ¹⁰⁰

2. As a new article of manufacture, packing composed of independently movable substantially flat lead strips, particles of finely fractured wood being between the several lead strips, and a fabric covering for said lead strips and finely fractured wood, substantially as described. ¹⁰⁵

3. As a new article of manufacture, a packing roll composed of a spiral fabric ¹¹⁰

constituting a covering for the roll, and
spiral layers consisting of independently
movable lead strips and particles of finely
fractured wood between the several lead
strips of each spiral layer, substantially as
described.

Signed at New York city in the county of

New York and State of New York this 4th
day of November, A. D. 1911.

CHARLES S. BAVIER.
EDWIN F. BANFIELD.
